UNITED STATES PATENT OFFICE.

HERBERT H. HART, OF EVANSTON, ILLINOIS.

METAL CAR-ROOF.

1,189,252.

Specification of Letters Patent.

Patented July 4, 1916.

Application filed February 7, 1913. Serial No. 746,716.

To all whom it may concern:

Be it known that I, HERBERT H. HART, a citizen of the United States, residing at Evanston, in the county of Cook and State 5 of Illinois, have invented certain new and useful Improvements in Metal Car-Roofs, of which the following is a specification.

My invention relates to car-roofs and the object thereof is to provide a novel and efficient structure of this kind from metal.

The construction of my new roof is such that greater strength and at the same time sufficient flexibility for practical use is provided and a maximum of headroom, and a 15 minimum of weight are afforded within the car. My new form of roof may be employed in connection with either the wooden or steel car construction although herein shown as applied to a car with wooden body.

20 In the drawings Figure 1 is a perspective of a portion of a car-roof embodying my invention, some of the roofing sheets being omitted and others broken away; Fig. 2 a section on the line 2—2 of Fig. 1 but on a larger scale; Fig. 3 a section on the line 3—3 of Fig. 1 but on the same scale as Fig. 2; Fig. 4 a plan view of a part of one of the purlins; Fig. 5 a cross-section on the line 5—5 of Fig. 4; Figs. 6 and 7 perspectives of 25 one of the end caps for the carlines; Fig. 8 a detail view of a modified form of the carline illustrating a somewhat different shape thereof; Fig. 9 a perspective of a portion of a car-roof illustrating a modified construction and arrangement of the purlins; Fig. 30 10 a plan view of one of the purlins of Fig. 9; Fig. 11 a section on the line 11—11 of Fig. 9 but on a larger scale; Fig. 12 a detail view of one of the purlins or a portion 40 thereof illustrating a different way of corrugating the same; Fig. 13 a view similar to Fig. 2 but illustrating a modification of the structure thereof; Figs. 14 and 15 detail views of additional modifications of the connection between purlins, carlines and sheets, and Figs. 16 and 17 detail views of a purlin 45 showing the corrugation thereof provided with a filler.

For the sake of brevity and clearness in 50 description I will describe my invention in connection with the herein illustrated embodiments in which my car-roof is shown applied to a car of the wooden body type, although it will be understood that my invention is equally applicable to all-steel cars or cars with metal bodies.

Referring to the particular embodiment of my invention, as illustrated in Figs. 1 to 5, the car body is here shown as consisting of the two opposite side plates 1, the end plates 2, of which only one is shown, the siding 3, fascia board 4 and ridge pole 5. The car roof in which my invention resides is composed wholly of metal, the same comprising a series of carlines 6, a series of purlins 7 and the roofing sheets 9, which parts are associated and connected together in any one of the several ways herein illustrated and hereinafter described.

As herein shown and by preference, each 70 carline is continuous from side to side of the car, that is the same is formed in a single piece extending from one side of the car and over the ridge pole to the other side of the car. Each carline is made of sheet metal of 75 the proper thickness and strength and in general is of channel shape, being composed of the two parallel portions or sides 6^a and the connecting portion 6^b forming the bottom of the channel. In addition and by 80 preference, the said portion 6^b is centrally longitudinally depressed in order to form the external groove 6^c, clearly illustrated in Figs. 1 and 2. Furthermore, each carline is provided with the laterally directed flanges 85 6^d which are here shown as at right angles to the sides 6^a of the channel section. In the particular construction now being described these flanges form a means of attachment of the carlines to the purlins and to the 90 roof frame.

Each purlin, in the construction shown in Figs. 1 and 2, is composed of a strip of metal of desired thickness and length and here shown as connecting two or more of the 95 carlines. As a matter of fact, each purlin may if desired run the full length of the car-roof, its opposite ends being secured in the end plates 2 of the roof frame. Each purlin, in its portion between two adjacent 100 carlines is suitably corrugated or grooved as at 7^a, such groove extending downwardly so that the purlin will present a substantially flat or straight surface to the roofing sheets to be applied as hereinafter described. 105 This corrugating of the purlin is to provide the greatest strength with the least thickness and width of the strip of metal, the preferable extreme condition in this regard being illustrated in Fig. 4 wherein the metal 110 of the purlin is shown as drawn inwardly from its opposite sides in order to provide

said corrugation. This, however, is not essential so long as the required strength is imparted nor is any corrugating at all necessary in the broader aspect of my invention. Furthermore, the corrugating may partake of a somewhat different character as shown in Fig. 12, wherein the purlin 7' is illustrated as provided with a plurality of substantially parallel corrugations 7" extending transversely of the purlin.

Those portions of the purlin which are connected with the carlines are offset to form a seat 7" to receive the flanges 6" of the carlines. As shown in Fig. 2 the purlins have upwardly raised portions 7" which in general are of channel section so as to extend upwardly and fit into the channel section of the carlines, thereby interlocking therewith. The carlines and purlins are connected together in suitable manner as by rivets 8 which hold them without interfering with the flexible or semi-rigid character of the roof.

In the present instance the roof proper is formed into a series of roofing sheets each of which, like the carlines, extend continuously from side to side of the car-roof. Each roofing sheet 9 is formed of a channel section corresponding with the outer contour of the carlines and adapted to fit upon and interlock therewith as clearly shown in Fig. 2. By preference this channel formation is provided at both longitudinal edges of each roofing sheet so that when the sheets are applied and in place on the roof, the meeting edges of two adjacent sheets will overlap each other and both of such thicknesses will be superimposed upon their carline as seen in Fig. 2. As there illustrated, the right-hand edge of the sheet shown at the left-hand end of Fig. 2 will overlap and cover the left-hand edge of the next sheet to the right while the right-hand edge of this latter sheet will overlap and cover the left hand edge of the next adjacent sheet on the right, and so on.

The described construction and connection of the parts provides a substantially integral and semi-rigid construction of car-roof. The interlocking of the parts hold them together sufficiently and provides the desired elasticity but in case an absolutely rigid roof is desired means which are shown in Fig. 14 as a series of rivets 10 pass through the two thicknesses of sheets, the flanges and the offset portions of the purlins. As above suggested these rivets are not necessary but may be dispensed with so far as the sheets are concerned inasmuch as the sheets are securely held by the attachment of their ends and by their interlocking with the carlines. At the side edges of the roof where the carlines rest upon the side plates 1, the rivets or screws may pass through or into such side plates.

The ends of the carlines are closed and sealed by means of a series of end caps, each of which, as illustrated in Figs. 1, 6 and 7, consists of a body or plate portion 11 fitting upon or embedded in the fascia board and having an inwardly directed right-angle portion 11" which is of channel section corresponding to the channel section of the carlines whereby, when the end cap is in place, it is adapted to fit into and interlock with 75 its carline. The plate or body portion of each cap extends upwardly sufficiently to form a flange 11" and adapted to abut against the outer end of its carline. In addition, said flange of each cap is provided 80 with a groove 11" corresponding and registering with the groove 6" of its carline. Furthermore, the inner face of each plate 11 is grooved or hollowed out at 11" to form an air space connecting with the interior of the 85 channel section of its carline. As shown in Fig. 1 the roofing sheets not only envelop the carlines but also these end caps, each sheet having end flanges 8" which extend over the edges of the roof and are secured to 90 the fascia board in suitable manner as by means of the fastening devices 12 which may be rivets, screws, bolts or the like as may be desired.

So far as my invention in its broader 95 aspect is concerned, it is not necessary that the purlins have the upwardly raised portions 7" for if desired the seat portions of the purlins may be run straight as indicated at 7" in the modified form illustrated in Fig. 100 13. Moreover, as shown in the modification of Fig. 14 both the carline and purlin may have straight or plain channels 6" and 7" respectively. Furthermore, in case of the construction shown in Fig. 15 fastening 105 bolts 13 may be employed, the same passing through the bottom portions of the channels of the carlines and the purlins such as shown in Fig. 2 for securing them firmly together. According to this modified form of construction of Fig. 15, the arrangement and 110 formation of the roofing sheets are somewhat different. As shown each sheet 14 extends merely between two adjacent carlines, the opposite longitudinal edges being provided with upwardly or outwardly directed flanges 14". Over each carline and also over 115 said flange 14" extends a cap 15 consisting of a long strip of channel section to accomplish the object in view and having in addition flanges 15" along its opposite longitudinal edges. For securing the carlines and purlins together, rivets 16 or the like may be employed, and these rivets may, if desired, pass also through the roofing sheets 120 125 and the cap, in the manner illustrated in Fig. 14.

The carlines may be of any suitable or desirable cross-section such as illustrated in the figures already described and also as 130

illustrated in the modification of Fig. 8 wherein the carline 17 is shown of more rounded form as regards the bottom formation of the channel and the groove therein.

6 According to the construction illustrated in Fig. 1 the purlins may be made more or less continuous that is each purlin may connect more than two of the carlines but it will be obvious that each purlin may connect merely two adjacent carlines in which event each purlin will consist of a metallic strip 18 connected at its ends with the flanges 6^a of the carlines as clearly shown in Figs. 9 and 11. Furthermore, it is obvious that these purlins may be arranged in staggered order as illustrated in Fig. 9. Moreover, the depression or cavity formed in the trussed purlins of the different forms shown may be provided with a suitable filler, such as wood 19 (see Figs. 16 and 17) or the like thereby affording a complete and continuous support for the roofing sheets as to the entire top surface of the purlins.

I claim:

25 1. In a car roof, the combination of a carline and a purlin connected therewith, the latter consisting of a metallic strip having its body portion corrugated downwardly to form a truss support and having a depressed portion forming a seat for the carline, said depressed portion beginning substantially at one end of said corrugation whereby the strain of the carline on the purlin is communicated directly to the truss and sustained thereby, the top surface of the purlin being otherwise flat, and a roofing sheet supported by said flat surface and by the carline.

2. In a car roof, the combination of a series of carlines and a series of purlins connected therewith, each purlin consisting of a metallic strip having its body portion between the carlines corrugated downwardly to form a truss support and having its portions adjacent the carlines depressed to form seats therefor, said depressed portions beginning substantially at one end of said corrugation whereby the strain of the carline on the purlin is communicated directly to the truss and sustained thereby, the top surface of such body portion of the purlin and the top surface of those portions of the carlines seated in the purlins being flat and flush with each other, and a roofing sheet supported by said flat surfaces of the carlines and purlins.

3. In a car roof, the combination of a carline of channel form provided with a laterally extending flange, a purlin connected therewith and consisting of a metallic strip having a portion offset to the extent of the thickness of said flange and received by the latter and also having an upwardly directed portion interlocked with the channel of the carline, and a roofing sheet fitting upon the

purlin and said flange which present a flush surface to the sheet.

4. In a car roof, the combination of a series of carlines of channel section, metallic purlins having channel portions received by and interlocked with such channel of the carlines, and roofing sheets interlocked with the carlines and supported by the purlins.

5. In a car roof, the combination of a carline of channel form provided with a laterally extending flange, a purlin connected therewith and consisting of a metallic strip having a portion offset to the extent of the thickness of said flange and received by the latter and also having a channel portion received by and interlocked with such channel of the carline, and a roofing sheet interlocked with the carline and fitting upon the purlin and said flange of the carline which present a flush surface to the sheet.

6. In a car roof, the combination of a series of carlines of channel section each consisting of two parallel portions and a connecting portion, the latter being inwardly depressed to form a longitudinal groove, roofing sheets interlocked bodily with said carlines and having portions fitting into their said grooves, and purlins connected with the carlines.

7. In a car roof, the combination of a series of carlines of channel section, each consisting of two parallel portions, a connecting portion and two outwardly directed side flanges, said connecting portion being inwardly depressed to form a longitudinal groove, purlins having upwardly directed portions received by the channel of the carlines and meeting the said inwardly depressed portions thereof, and roofing sheets applied to the carlines and purlins.

8. In a car roof, the combination of a series of carlines of channel section, each consisting of two parallel portions, and a connecting portion, the latter being inwardly depressed to form a longitudinal groove, caps for closing and sealing the ends of the carlines, each cap consisting of a plate with a projecting portion corresponding with the carline and extending thereinto, said plate having a groove corresponding with and forming a continuation of the groove formed by the interlocking of the sheet into the groove of the carline, and roofing sheets interlocked with said carlines and fitting into their said grooves.

9. In a car roof, the combination of a series of carlines of channel section, each consisting of two parallel portions and a connecting portion, the latter being inwardly depressed to form a longitudinal groove, caps for closing and sealing the ends of the carlines, each cap consisting of a plate with a projecting portion corresponding with the carlines and extending thereinto, said plate having a hollow portion forming an air

space in connection with the interior of its carline, and roofing sheets interlocked with said carlines and fitting into their said grooves.

5 10. In a car-roof, the combination of the metal carlines 6 each comprising an upwardly projecting channel portion consisting of side walls 6^a and connecting web 6^b, purlins 7 having upwardly projecting portions 7^c interlocking with the said channel portion of two adjacent carlines, and roofing sheets connected with the carlines.

11. In a car-roof, the combination of the metal carlines 6 each comprising an upwardly projecting channel portion consisting of side walls 6^a, and connecting web 6^b having a central depression 6^c, purlins 7 connected with the carlines, and roofing sheets interlocked with said channel portion of the carlines and having a depression fitting said depression 6^c.

12. In a car-roof, the combination, with

channel shaped carlines, of purlins having channels interlocking with the channels of the carlines, and means for connecting said channels of the carlines and purlins.

13. In a car-roof, the combination, with channel shaped carlines, of purlins having channels interlocking with the channels of the carlines, and a bolt passing through said channels of the carlines and purlins.

14. In a car-roof, the combination, with carlines each having a longitudinal channel with a longitudinal groove in the bottom of such channel, purlins each having a transverse channel, and bolts engaging said channels of the carlines and said channels of the purlins for securing the carlines and purlins together.
